UNITED STATES PATENT OFFICE

2,481,788

KEEPER FOR STRAPS AND CORDS

Lester L. Sherwood, Los Angeles, Calif.

Application June 27, 1945, Serial No. 601,741

4 Claims. (Cl. 24—182)

1

My invention relates to a keeper for straps, cords and the like and has for its principal object to provide a simple, practical and inexpensive keeper which may be advantageously employed for receiving, holding and guiding, straps, cords and ties used on ladies' hand bags, traveling bags and cases, awnings, tents or the like and the construction of the keeper being such, that it may be easily and quickly applied to or removed from the leather, fabric or other flexible material, of which the strap or cord bearing member is formed.

A further object of my invention is, to provide a keeper of the character referred to, which is formed from a single piece of wire, bent to provide one or more strap or cord receiving loops and a pair of prongs, which latter are adapted to pass through fabric, leather or the like and thereby anchor the keeper in its applied position.

With the foregoing and other objects in view, my invention consists in certain novel features of construction and arrangement of parts, which will be hereinafter more fully described and claimed and illustrated in the accompanying drawings, in which:

Fig. 1 is a perspective view of a pair of the keepers.

Figs. 2 and 3 are perspective views of modified forms of keepers, each having a strap receiving loop and a pair of cord receiving loops.

Figs. 4 and 5 are perspective views of keepers each having a strap receiving loop and a single cord receiving loop.

Fig. 6 is a plan view of a pair of the keepers applied for use on an article of leather or fabric.

Fig. 7 is a vertical section taken on the line 7—7 of Fig. 6.

Figs. 8 and 9 are perspective views of modified forms of the keeper, each having a strap receiving loop and a pair of cord receiving loops.

Fig. 10 is a plan view similar to Fig. 6 and showing a stay or retaining plate applied to the loops of a pair of the keepers.

Fig. 11 is a vertical section taken on the line 11—11 of Fig. 10.

Fig. 12 is a perspective view of keepers constructed in accordance with my invention and shaped to form a hook and eye.

Fig. 13 is a plan view showing a hinge composed of a pair of the keepers and a short strap.

Fig. 14 is a vertical section taken on the line 14—14 of Fig. 13.

Fig. 15 is a sectional view showing the keepers used in forming a swivel.

All forms of my improved keeper are formed from a single piece of wire and to produce the form shown in Fig. 1, the wire is bent to form a substantially rectangular loop comprising spaced parallel members 10 and 11, short parallel members 12 and 13 connecting the ends of members 10 and 11, and a prong member 14 which projects outwardly away from the lower end of member 12 in longitudinal alignment with member 11, which latter also functions as a prong.

10 The free end of prong 11 is spaced a short distance from the juncture of end member 12 with prong 14.

The keeper members thus formed are generally used in pairs with the loop portions disposed side by side, with prong members 11 and 14 inserted through the fabric or leather of a bag, awning or the like and lying immediately beneath same and with the prongs of one loop projecting in the opposite direction from the prongs of the other loop. (See Figs. 6 and 7.)

15 Thus the two loops comprising the parts 10, 12 and 13 lie side by side above the fabric or leather and provide a secure keeper for the strap or tie inserted through the loops.

20 In Fig. 2 I have shown loop member 10a formed with two externally arranged circular loops 15 for the reception of cords or small cables and in Fig. 3 a pair of internally disposed cord receiving loops 16 are formed on member 10b.

25 Figs. 4 and 5 show respectively, on member 10c, small internally and externally arranged single loops 17 and 18 for the reception of cords or the like.

30 In Figs. 8 and 9, I have shown forms of keepers adapted to receive either straps or cords, with the small cord receiving loops such as 19 and 20, formed at the corners between member 10f and end members 12f and 13f.

35 To provide a stay or reinforcement for the keepers, a narrow plate 21 of metal or plastics is provided with a longitudinal slot 22 through which pass the loop members such as 10g with said plate resting on the surface of the leather or fabric to which the keeper is applied. To maintain the plate and keeper members in assembled relation, the lower portions of the vertical members 12g and 13g are indented as designated by 23 for the reception of the edges of the plate at the ends of slot 22. (See Figs. 10 and 11.)

40 In Fig. 12, I have shown a hook and eye arrangement produced in accordance with my invention, and in this structure each member is formed from a single piece of wire bent to form an eye such as 24 or a hook such as 25 with the end portions of the wire forming each member

2

extended in longitudinal alignment to form prongs 26.

In Figs. 13 and 14 I have shown a pair of the keepers used in the formation of a simple and effective hinge, and in this structure the prongs of the keepers 27 are inserted through the parts to be connected, adjacent their edges, and a strap 28 passes through said keepers, with the ends of said strap secured to the parts of the hinged structure, by stitching or otherwise.

To provide a swivel connection between a strap, rope or the like and a member such as an awning, sail or tarpaulin, two of the keeper loops having long members such as 12h are arranged side by side, with said members passing through the fabric and through washers such as 30 disposed on one or both sides of the fabric (see Fig. 15).

Thus it will be seen that I have provided a keeper for straps, ties, cords and the like, which is simple in structure, inexpensive of manufacture, and very effective in performing the functions for which it is intended.

It will be understood that minor changes in the size, form and construction of the various parts of my improved keeper may be made and substituted for those herein shown and described without departing from the spirit of the invention, the scope of which is set forth in the appended claims.

I claim as my invention:

1. A keeper for straps and the like comprising a pair of identical members each formed from a single piece of wire and comprising a substantially rectangular loop, open at one of its lower

corners and with the terminal portion of the wire forming said loop extending outwardly from said open lower corner in longitudinal alignment with the opposite terminal portion of the wire which forms the lower member of said loop.

2. The keeper as set forth in claim 1, with said loops disposed side by side in reversed arrangement so that the outwardly projecting terminal portions of the loop forming wire project in opposite directions.

3. The keeper as set forth in claim 1, with a slotted plate removably applied to said loops above the projecting terminal portions thereof.

4. The keeper as set forth in claim 1, with a slotted plate removably applied to said loops above the projecting terminal portions thereof and the wire at the ends of said loops being indented for engagement with said plate at the ends of the slot therein.

LESTER L. SHERWOOD.
